ACTUATING MEANS FOR ROTARY DRUM-
TYPE VENDING MACHINESHarry Galin, Yonkers, and Lawrence Reiss,
New Rochelle, N. Y.

Application May 7, 1952, Serial No. 286,581

2 Claims. (Cl. 221—82)

1

This invention relates to coin-controlled operating mechanisms for vending machines of the type in which articles are dispensed from a rotary drum.

The invention may be used in a vending machine having a cabinet in which there is at least one drum or magazine mounted for rotation on a horizontal axis and having around its periphery compartments to hold the individual articles to be dispensed, the drum also having on one side an annular series of laterally projecting pins which correspond in number to the compartments. The invention embodies a coin-released mechanism which coacts with the pins and which may be actuated by hand or by power to give the drum a step-by-step rotary movement to successively align the compartments with an exit chute so as to vend or dispense one of the articles each time a coin is inserted in the machine and the mechanism is actuated.

The object of the invention is to provide a simple, effective and practical mechanism of the above indicated character for giving the magazine or drum a step-by-step rotary movement.

With the above and other objects and advantages in view, the invention resides in the novel combinations and arrangements of parts and the novel features of construction hereinafter described and claimed, and illustrated in the accompanying drawings which show the present preferred embodiment of the invention.

In the drawings:

Fig. 1 is a vertical front-to-rear sectional view through portions of a vending machine embodying the invention, parts being broken away and parts being conventionally shown;

Fig. 2 is a detail view similar to portions of Fig. 1 but showing the parts of the drum actuating mechanism in different positions;

Fig. 3 is a detail horizontal section taken on line 3—3 in Fig. 1; and

Fig. 4 is a detail vertical section taken on line 4—4 in Fig. 1.

Referring more in detail to the drawings the numeral 10 denotes generally a suitable cabinet or casing which may have a rear wall 11, a top wall 12 and a front wall 13. The upper portion 14 of the front wall may be in the form of a hinged or removable door to give access to the interior of the cabinet; and if desired, the top may have a suitable opening 15 closed by a hinged door or cover 16.

In the upper portion of the casing is a cylindrical drum 17 mounted for rotation about a horizontal axis 18 which may be carried by a

suitable bracket or brackets 19 fastened either to the back or to the top wall 12. The magazine or drum 17 may consist of two laterally spaced circular plates 20 connected by a cylindrical band 21 spaced inwardly from the edges of the plates and by an annular series of regularly spaced radial plates 22. The latter in connection with the band 21 and the outer portions of the side plates 20 form outwardly open compartments 23 of a size to hold the articles to be dispensed. As shown, the peripheral compartments or receptacles 23 are intended to hold cylindrical bottles or cartons C for milk or a drink, and when the machine is used to vend such packaged beverages, it will be understood that at least the portion of the cabinet containing the drum may be suitably refrigerated. The articles C in the lower half of the drum may be retained in their compartments by an arcuate bottom plate 24 which has an opening in communication with the upper end of an exit or discharge chute 25 for the articles. On one side face of the drum is an annular series of laterally projecting pins 26 disposed slightly inward of the outer edge the plate 20 to which they are fixed. These equally spaced pins 26 correspond in number to the compartments and serve as latch engaging lugs or shoulders as hereinafter described.

The drum controlling and actuating mechanism is mounted in the cabinet beneath the drum and may be supported on a forwardly and rearwardly extending frame member 27 and the housing 28 of any suitable coin actuating mechanism. The member 27 is shown as a vertical plate disposed slightly outward of the plane of the drum plate 20 which carries the pins 26. The housing 27 is shown as set into the front wall 13 beneath the door 14, but the mechanism within the housing is diagrammatically illustrated since it is old and the details of its form no part of the present invention. It comprises a coin receiving chute 29 leading to a slug ejector 30 associated with a coin mechanism 31. The latter includes a pull-and-push rod or plunger 32 having a suitable finger piece or handle 33 exposed at the front of the cabinet. As is common, the coin mechanism locks the plunger 32 against movement until a proper coin is dropped into the outer exposed end of the chute 29. The coin mechanism includes a reversible pawl 34 and a coacting rack or ratchet 35 which necessitates a full stroke of the plunger or operating member 32 in either direction when once it has been started in either direction. While the above outlined old mechanical means may be employed for operating the improved

drum actuating means, it is to be understood that the latter may be operated by any suitable electrical operating mechanism.

The improved drum controlling and actuating means includes a drum locking element 36, a lock-releasing and drum-actuating unit 37 and a second drum locking element 38, the latter preventing retrograde rotation of the drum. The element 38 is shown as a slidable spring projected dog having a beveled end to coact with the drum pins 26. It may comprise a plate with a longitudinal slot 39 to receive beaded screws 40 on an angle bracket 41 secured to the housing 28, so that the dog may slide in a direction radially of the drum pivot 18. The outer end of the plate 38 is bent at right angles to receive the thrust of a coil spring 42 interposed between it and an angle bearing secured to the bracket plate 41, the spring being held by a suitable guide rod as shown in Fig. 1. It will be seen that when the drum is rotated in the direction of the arrow A in Fig. 1, the pins 26 will engage the beveled end of the dog 38 and push it against the spring as they pass it, but the dog will prevent backward movement of the drum.

The first drum locking element 36 is also in the form of a slidable spring projected dog with a beveled end to coact with the pins 26. It is shown as an elongated upright plate or bar disposed against the frame plate 27 and formed with longitudinal slots 43 to receive beaded screws 44. The lower end of the bar is bent at right angles and apertured to receive the upper end of a rod 44, the lower end of the latter being slidable in an aperture in an angle bracket 46 fixed to the plate 27. A collar 47 is fixed to the rod 44 beneath the bent end of the dog or bar 36 and a coil spring surrounds the rod between the collar 47 and the bracket 46 to normally hold the upper end of the slidable lock 36 in the path of travel of the pins 26. The upper end of the locking member 36 is preferably beveled as shown at 49 to permit it to quickly clear or release the pin 26 with which it is engaged to normally prevent forward movement of the lower part of the drum in the direction of the arrow A. The locking member 36 carries near its central portion a laterally projecting stud 50 engageable by a portion of the unit 37 to retract the lock and release the drum.

The unit 37 includes an upright lever pivoted between its ends at 51 on the plate or support 27. The upper arm or portion of the lever 37 carries a pivotally mounted spring pressed latch 52 to coact with the pins 26 and also a laterally projecting arm 53 to coact with the stud 50. The arm 53 is laterally off-set and has at its end a flat portion 54 to engage the stud 50 and retract the lock member 36 as shown in Fig. 2, when the lever 37 is actuated. The upper end portion 55 of the lever is enlarged and from it is struck two ears 56 to receive a pivot 57 on which the latch 52 swings. The latch is a generally rectangular plate having at its lower end spaced ears to aline with the ears 56 and to receive the pivot pin so that the latch swings laterally with respect to the lever 37. A coil spring 59 is on the central portion of the pivot pin 57 and thrusts the upper portion of the latch toward the drum and in the path of the pins 26. One side edge of the latch is straight and adapted to drop behind a pin 26 while its other side portion is outwardly curved to form a cam 60. To remove strain from the pivot 57 the latch is formed with a slot 61 to receive a

guide pin or stud 62 fixed to the lever. The lower end of the lever 37 is suitably associated with the means which actuates it; but as shown it is formed with a longitudinal slot 63 to receive a lateral pin 64 on the plunger 32 so as to provide a pivotal and sliding connection. A coil spring 65 may be connected between the upper arm of the lever 37 and the housing 28 or other fixed part in the cabinet to move the lever to its normal position as shown in Fig. 1.

The operation of the mechanism is apparent from the foregoing but will be briefly described. With the parts in their normal position shown in Fig. 1, a coin is deposited in the slot of chute 29 and will cause the coin mechanism to unlock or release the plunger 32. The latter is then pulled outwardly to swing the lever 37 against the tension of spring 65. As the upper part of the lever swings to the position shown in Fig. 2 the arm 53 engages and moves the stud 50 downwardly to retract the lock member 36 from the pin 26 with which it was engaged and thus release the drum for forward rotation. At the same time the cam portion 60 of the latch 52 rides over the end of the pin 26 next to the one which is released by the lock member, the latch being thus swung laterally until its straight side edge drops in rear of the pin. When the operating member 32 is released, spring 65 pulls the lever back to its normal position, and as the upper end of the lever swings forwardly the latch 52, because of its engagement with the last mentioned pin 26, will cause the drum to be turned so that the article C in the compartment 23 immediately in rear of the chute 25, will drop into the latter. As soon as the latch begins to move the drum the arm 53 permits the locking member 36 to move upwardly under the action of spring 48 so that the lock will engage the next pin 26 and prevent the drum from turning forwardly more than the peripheral length of one compartment, the dog 38 preventing any retrograde rotation of the drum.

From the foregoing, taken in connection with the accompanying drawing, it will be seen that a novel and advantageous provision has been made for carrying out the objects of the invention, and while preferences have been disclosed, attention is invited to the possibility of making variations within the scope of the invention as claimed.

What is claimed is:

1. Actuating means for a rotary drum-type vending machine having a drum mounted for rotation on a horizontal axis and provided with peripheral compartments to hold articles to be dropped one at a time into a discharge, a case enclosing the drum and provided with an upright supporting plate disposed beneath the drum at one side of the latter, an annular series of pins associated with the compartments and projecting laterally from said one side of the drum, an upright drum locking bar slidably mounted on said plate and having an upper end to coact with said pins, said bar being spring actuated in an upward direction, a stud fixed to said bar and projecting laterally therefrom, an upright actuating lever fulcrumed between its ends on said plate to one side of said bar and having its upper end disposed adjacent the drum, an upright pin-engaging latch plate fulcrumed at its lower end on one side of said lever and having at its upper portion a laterally curved cam to ride over the ends of said pins when the lever is moved in one direction, spring means urging the upper portion of the latch plate to

ward said lever and into the plate of said pins, an arm rigid with the upper portion of said lever below said latch plate and projecting laterally from the lever for engagement with said stud to move said locking bar out of the path of said pins when the lever is moved in said one direction, means associated with the lower end of the lever to move it in said one direction, and spring means for moving the lever in the opposite direction.

2. The structure of claim 1 in which said means for moving the lever in said one direc-

tion is a coin-released sliding plunger with a sliding and pivoted connection to the lower end of the lever.
